FORM ROLLER SETTING AND TRIPPING
MECHANISM

Henri E. Peyrebrune, River Forest, Ill., assignor,
by mesne assignments, to Miehle Printing Press
and Manufacturing Company, Chicago, Ill., a
corporation of Delaware

Application May 22, 1947, Serial No. 749,803

4 Claims. (Cl. 101—352)

1

This invention relates to inking mechanism for sheet fed printing presses. It more specifically pertains to improved means whereby the form rollers can be set with respect to the printing plate for the purpose of establishing the desired contact relation therewith, and whereby these rollers can be tripped away from the plate either by hand or automatically, in order to interrupt the supply of ink thereto under certain conditions which may arise while a press is running.

In the operation of inking mechanism of the class to which my invention relates, the ink is applied to a printing plate or form by means of a series of form rollers which receive a supply of ink from an ink distributing roller system. Such rollers are set for the desired contact relation with the plate by manually operated means such as set screws or the like.

Under certain conditions which occur during the operation of sheet fed printing presses, for instance when a sheet is misfed, the form rollers must be tripped off the printing plate in order to interrupt the supply of ink thereto until normal feeding conditions of the sheets are again established. Heretofore, such tripping was accomplished by means independent of the roller setting means, and all the form rollers of a series were tripped off and on the printing plate simultaneously while passing over the gap provided in a plate cylinder for purposes well known in the art. With the introduction of improved sheet feeding and registering methods which permit of a smaller cylinder diameter and a gap therein of reduced span, for accommodating a given size sheet, not all of the form rollers pass the gap at the same time and therefore the rollers cannot be tripped off and on the cylinder simultaneously.

In view of this I propose to trip the form rollers off and on the printing plate in sequence, preferably in pairs.

Stating the principle of the invention broadly, it consists in the provision of mechanism whereby form rollers, which apply the ink to the printing plate, can be positively moved into their ink applying position and tripped therefrom sequentially and by the same means whereby the setting of the form rollers with relation to the printing plate is accomplished.

This I propose to carry into effect preferably by means of eccentric adjusting means arranged so that the same eccentric means, whereby the form rollers are set with relation to the printing plate, are used also for tripping the rollers with relation to the plate.

2

Another accomplishment and object of the invention includes the provision of eccentric means for setting the form rollers with relation to a cooperating roller or rollers of the ink distributing system.

An additional object of the invention resides in the provision of means whereby the form rollers may be automatically tripped, preferably sequentially and in pairs, by the intermediary of the same eccentric means whereby the form rollers are set with relation to the plate and by the use of one actuating cam only.

A further object of the invention is to arrange the setting and tripping means for the form rollers in such a manner that when the rollers are tripped from the printing plate they remain in proper contact relation with their respective associated distributing roller or rollers.

Another object resides in the provision of eccentric means whereby the form rollers are set for contact relation with their associated ink distributing rollers.

Still further objects and advantages of my invention will become apparent from the following description and appended claims read in conjunction with the accompanying drawings in which,

Figure 1 is a roller diagram which illustrates the general arrangement of the various elements included in the inking mechanism of a printing press;

Figure 2 represents schematically the relative position of a series of form rollers in operative position with respect to a printing plate carrier, preferably a cylinder, and to the associated ink supplying or distributing rollers, together with the eccentric means whereby the form rollers are moved manually toward and from the plate as well as with respect to the associated distributing rollers;

Figure 3 illustrates in plan view a preferred arrangement of a form roller with respect to its supporting means and the parts involved in the setting of such roller;

Figure 4 represents a view taken along such lines with reference to Figure 2 as will illustrate in partial cross section those relative parts whereby the setting with relation to a form roller may be accomplished;

Figure 5 illustrates the position of part of the operating means and shows all the form rollers tripped from the printing plate, and

Figure 6 represents a diagrammatic showing of the mechanism associated with the eccentric means whereby the form rollers are automatically and sequentially moved into and out of

their operative positions, one pair of said rollers being indicated as tripped from the plate while the other pair is in contact therewith.

As illustrated in the roller diagram Figure 1, a conventional inking mechanism to which the principle of my invention may be applied, includes an ink fountain and roller 10, a doctor roller 11 whereby a supply of ink is conveyed from the fountain roller to a vibrator roller 12 and with which latter are associated a number of rider rollers such as 13 and ink-up roller 14. From the vibrator roller 12 the ink is then conveyed by means of additional rider roller 13, vibrating drum 15 so that a thin film of ink is eventually applied to the distributing rollers 16 and 17 which are in contact with the form rollers 18 whereby the ink is finally applied to the printing plate 19 carried by the plate cylinder 20. The composition rollers are shown in heavy lines, whereas the metal rollers such as 12, 15, 16 and 17 are shown in thin lines.

It will be noted that in Figures 2 and 5, only part of the inking mechanism frame 21 is shown in full lines and that only some of the rollers which comprise the ink distributing roller unit are shown, these are indicated in broken lines. Furthermore, the printing plate 19, together with its support 20, preferably in the form of a cylinder, are also indicated in broken lines for the purpose of a clearer showing of those parts actually involved in the invention. Moreover, in Figures 6 only those parts are shown in full lines which constitute the means whereby the form rollers are tripped from their ink applying position when so required.

It shall also be understood that the parts illustrated in Figures 2 and 5, and some of those indicated in Figure 6, as being applied to the side frame member 21, are duplicated on the frame member 22 at the opposite side of the inking mechanism, see Figure 3, and that the manner of operation is identical at both sides.

Referring now to Figure 2 of the drawings, the form rollers 18 are supported in their respective sockets 28, 29, 30 and 31 which are provided on the arms 32, 33, 34 and 35. The latter are held in their positions with relation to the frame 21 by means of a retaining ring sector 37 in a manner that the lower ends of these arms may move freely to follow any adjustment imparted to them as will be explained later with reference to Figure 4. The sector 37 is preferably secured to the side frame 21 by means of bolts 38. The free ends of the arms 32 to 35 are carried by means of eccentric bearings 41 to 44 inclusive in a manner that by the actuation of these eccentrics, the arms 32 to 35 and therewith the form rollers 18 may be moved down or up for the purpose of contacting the form rollers with or tripping them from the plate 19 on the cylinder 20.

The adjustment of the form rollers 18 may be effected manually by means of hand levers 47 two of which are illustrated in Figure 2, and which are mounted for engagement at the outer side of the frame 21, see Figures 3 and 4.

It will be understood with reference to Figure 4, that upon rotation of the eccentric 42 by means of the hand lever 47, or automatically as will be explained hereinafter, the arm 33 will be moved up or down, as the case may be, in order to either trip the roller 18 from the printing plate, or lower it into contact therewith, and that during such movement the lower end of the arm 33 can slide freely between the frame 21 and the retaining ring sector 37, sufficient clearance being

provided for such movement between the frame and said sector.

For the purpose of establishing the desired contact pressure between the form rollers 18 with relation to their respective distributing rollers 16 and 17 which are mounted on fixed axes, links 48 to 51 are pivoted to each one of the arms 32 to 35. The outer ends of these links are supported in eccentric bearings such as are indicated at 52 and 53 in Figure 2. This arrangement applies, of course also, to the other form rollers 18 which have contact relation with the distributing roller 17.

This adjustment is preferably accomplished by suitable hand levers such as at 54 and 55 which are also operable from the outer side of frame members 21 and 22. It will be seen therefore that with the arrangement so far described independent manual adjustment of the form rollers with relation to the printing plate as well as with relation to the distributing rollers 16 and 17 can be effected.

The plan view as presented in Figure 3 and the sectional view given in Figure 4, are essentially limited to the showing of the manually operated roller setting means such as are represented in Figure 2, the automatic tripping mechanism for the form rollers having been intentionally omitted from Figures 2 and 4 inclusive and are illustrated in Figures 5 and 6.

Moreover, in Figure 4, the cross section is taken along such lines as will illustrate the relative arrangement of merely one form roller supporting arm and the eccentric means whereby the latter is actuated. The eccentric 42 is shown all the way up, consequently the roller 18 is tripped off the plate 19, a position indicated in Figure 5.

Referring now to the detail construction depicted in Figure 4, it will be seen that the hand lever 47, whereby the eccentric 42 is actuated, is applied to the free end of the eccentric carrying shaft 56 which projects through the side frame 21. A preferred mounting for this and all other levers which have the function of adjusting an eccentric by hand, preferably includes set pins 58 driven into or otherwise secured to the shafts which carry the eccentric bearings. The levers are positioned by means of these set pins 58 and are secured into their positions by applying a nut 59 to the threaded ends of said shafts.

The form rollers are preferably held within their respective sockets and are supported therein by means of anti-friction bearings 61 and 62 mounted at the ends of said rollers, see Figure 3, the former one of which bearings may be retained against lateral movement within a groove 64 formed in the socket 29 of lever 33, whereas the bearing 62 at the opposite end of the form rollers is not restrained against any lateral movement within its supporting socket.

The links 48 to 51 inclusive are preferably pivoted to the arms 32 to 35 respectively by means of a threaded stud 66 which passes through a bore 67 provided in the lower end of said links and which projects through bore 68 formed in said arms in alignment with the axis of the form rollers 18. The studs 66 have a shoulder 69 which bears against the roller socket arm 33, and the stud is secured thereto by means of a nut 70.

In Figure 5, which illustrates part of the mechanism whereby the form rollers 18 are tripped automatically with relation to the plate 19, said form rollers are indicated in their position when

they are tripped from the plate, a position which they assume upon rotating the eccentrics 41 to 44 inclusive to the extent that the thick portion of the eccentrics is all the way up as shown in this figure.

According to the preferred arrangement of the operating elements illustrated in Figure 5, the form rollers 18 are tripped in pairs from the plate 19 by moving about the pivotal center of the links 48, 49, etc., thereby changing their angular relation while remaining in contact with their associated distributing rollers 16 and 17.

As shown in this figure, the eccentrics 41 and 42 are interconnected by a link 75, connecting rod 76 and the arm 77 of a bell crank lever 78. To the arm 79 of this bell crank lever is pivoted a connecting rod 80, the outer end of which link is in turn pivoted to a link 81 rigidly mounted on a rock shaft 82.

The eccentrics 43 and 44 are similarly connected by a system of links 83, connecting rod 84, bell crank lever 85, connecting rod 86 and lever 87 which latter is rigidly secured to a rock shaft 88.

It will be understood therefore that upon rocking of link 81 by means of the shaft 82, in an anti-clockwise direction, from its position shown in Figure 5, the eccentrics 41 and 42 will be rotated to assume the position depicted in Figure 2 where the rollers 18 are in contact with the plate 19, while maintaining contact however with their associated distributing roller 16.

In Figure 6 I have illustrated a preferred mechanism whereby the rollers 18 can be tripped automatically with respect to the printing plate 19 through the intermediary of the lever and link arrangement illustrated in Figure 5. This mechanism may include a closed cam 90 having a roller track 91, tripping levers 92 and 93 on the inwardly extending arms of which are carried cam rollers 94 and 95, respectively. These rollers ride within the cam track 91 and the levers 92 and 93 are pivoted to studs 97 and 98 respectively and are rocked about these studs by the motion imparted to them by the cam rollers 94 and 95 during the rotation of the cam 90 as will be readily understood.

Each one of said levers 92 and 93 is provided with suitable recesses and with bearing faces 99 and 100 for engagement by tripping dogs 101 and 102 which have corresponding bearing faces arranged for engagement with the faces 99 and 100, for the purpose that will be explained more fully hereinafter.

The dogs 101 and 102 are pivoted at 104 to links 105 and 106 respectively in a manner that said dogs can be rocked in order to move their bearing faces into and out of engagement with the bearing faces 99 and 100 of said tripping levers.

To the pivots 104 are also applied connecting rods 107 and 108, the former having in turn pivotal engagement with a lever 110 which is rigidly mounted on the rock shaft 82, while the connecting rod 108 has pivotal connection with a lever 111 which is likewise rigidly mounted on the rock shaft 88.

It will be readily understood that any conventional means, such as toggle springs, not shown, may be applied to the shafts 82 and 88 for the purpose of holding the link and rod connections and therewith the form rollers 18, either in "tripped off" or "on" positions.

To the dogs 101 and 102 are also pivotally attached connecting rods 112 and 114 which in

turn are pivoted to one arm of bell crank levers 115 and 116 respectively.

For the purpose of maintaining these dogs in their respective positions, I preferably apply "two-way" spring means, not shown, to these connecting rods.

To the other arms of said bell crank levers are pivoted connecting rods 117 and 118 respectively which extend to conventional automatically or manually operated tripping and set up means, the purpose of which is well known in the operation of printing presses and similar machinery where rollers or cylinders are to be tripped for various reasons out of their operative positions.

As indicated in broken lines in Figure 6, that pair of form rollers 18 which cooperates with the distributing roller 16 is indicated as being in contact with the printing plate 19. The upper bearing face of the dog 101 is in engagement with the bearing face 99 of the tripping lever 92, whereas that pair of form rollers 18 which cooperates with the distributing roller 17 is shown tripped from the plate 19, i. e. from the cylinder 20, and the dog 102 has assumed a position wherein its lower bearing face is in engagement with the bearing face 100 of the tripping lever 93.

The mode of setting the form rollers 18, and the manner of operation of the mechanism for tripping them will now be described.

Having reference to Figure 2, the form rollers 18 are first set for contact with their associated distributing rollers 16 and 17, by rotating the respective handles 54 etc. and therewith the associated eccentrics 52 etc. Then by means of the handles 47 the eccentrics 41 to 44 are rotated so that the form rollers are moved down and applied to the printing plate 19. During such downward movement the rollers 18 move closer to each other by riding over the surface of their associated distributing rollers and by remaining in contact therewith, the rollers 18 being guided during such movement by means of the links 48, 49 etc.

The cam 90, which is mounted on a shaft 120, is assumed to rotate in a clockwise direction as indicated by the arrow in Figure 6. Furthermore assuming for example that because of misregistration of a sheet fed to the printing press, the conventional set up means herein referred to have been actuated as is well known by detector mechanism for the purpose of tripping the press and therewith its inking mechanism, the dog 102, by the actuation of the connecting rods 114 and associated members, has been rocked to assume the position shown in Figure 6. In other words, the cam roller 95 is at such point within the track 91 where that pair of rollers 18 associated with the distributing roller 17 have already been tripped i. e. moved away from the plate 19, thereby interrupting the ink supply to the plate from these two form rollers.

The position of the roller 94 in the track 91 however, is such that the form rollers 18 associated with the distributing rollers 16 are about to trip off the plate 19.

The tripping of all the form rollers 18 either away from the plate, or into contact with it, is accomplished while said rollers pass over the gap 121 provided in the cylinder, see Figures 1 and 6, and within which gap are arranged, as is well known in the art, any suitable clamping means 122 for strapping a printing plate to the form cylinder 20.

With the dog 102 in the position shown, the tripping lever 93 can continue its rocking motion

about its shaft 98 transmitted by the roller 95 while following the track 91 of cam 90, because the face 99 of said lever, during its downward movement, will clear the dog 102 and no further movement will be transmitted to that pair of rollers 18. It will also be noted that upon tripping of the form rollers 18 from the plate 19, contact with their associated distributing rollers will be maintained.

During the tripping action of the lever 93 and associated dog 102, the link 106 was moved upwardly through the intermediary of the connecting rod 108 and arm 111, following the rocking movement of shaft 88 in an anti-clockwise direction, see Figure 6, thereby depressing the connecting rod 86, rotating the bell crank lever 85 in an anti-clockwise direction and thereby rotating the eccentrics 43 and 44 due to their connection with the arm 85 by means of connecting rod 84 and link 83. These eccentrics will then be all the way up thereby raising the arms 34 and 35 and tripping the form rollers 18 from the plate 19, a position indicated both in Figures 5 and 6. The tripping of these rollers occurred during the passing of the gap 121 beneath them.

The cam roller 94 associated with tripping arm 92 has assumed a position where the operating face 99 of said arm is brought into operative engagement with the upper bearing face of the dog 101, so that during continued rotation of the cam 90 the dog is urged downwardly and the link 105 is rotating in a clockwise direction about the stud 97. This position of dog 101 having been transmitted to it through the intermediary of the connecting rod 112, bell crank lever 115, and connecting rod 117 which latter as indicated herein is associated with any conventional tripping or set up means.

During this movement of the dog 101, namely to the right as viewed in Figure 6, the connecting rod 107 will be pulled down and the rock shaft 82 through the lever 110 secured thereto will be rocked in a clockwise direction.

This rocking motion of the shaft 82 is then transmitted through arm 81, connecting rod 80 and bell crank lever 78, connecting rod 76 and link 75 to the eccentrics 41 and 42 which then will assume the position shown in Figure 5, and consequently that pair of form rollers 18 associated with the distributing roller 16, will trip away from the plate 19 while maintaining contact with the roller 16. This tripping also takes place during the passing of the gap 121 beneath said form rollers.

Upon re-setting the conventional automatic tripping and set up mechanism, the dogs 101 and 102 will assume position opposite to those shown in Figure 6, so that upon rotation of the cam 90 through the cam rollers 94 and 95, the operating face 100 of the tripping lever 92 will be brought into association with the lower operating face of the dog 101, whereas the operating face 99 of the tripping lever 93 will engage the upper operating face of the dog 102, thereby the movement of the respective operating parts for the eccentrics 41, 42, 43 and 44 will be actuated in a direction opposite to that just described in connection with the tripping of the form rollers away from the plate. Consequently the form rollers 18 will again assume contact relation with the plate and while the gap 121 passes beneath them. In that position of the parts when the form rollers are in contact with the plate 19, no further motion will be transmitted to the dogs 101 and 102 by their associated tripping levers 92 and 93 upon

the continued rotation of the cam 90 until through some reason or other the automatic tripping and setting up mechanism is again actuated.

It shall be understood that while I have described a preferred arrangement of parts and operating mechanism therefor, many modifications thereof may be introduced without departing from the principle of my invention and therefore, I desire to cover any such changes in the arrangement of parts and their operating mechanism as will come within the scope and meaning of the appended claims.

What I claim is:

1. Inking mechanism for printing presses and the like, comprising in combination, ink distributing rollers having fixed axes, a series of form rollers arranged to receive a supply of ink from said distributing rollers and to apply a film of ink to a printing plate, eccentric means for establishing contact relation of the form rollers with said distributing rollers, additional eccentric means for manually setting said form rollers in contact relation with the printing plate, and mechanism for automatically actuating said latter means to trip said form rollers with respect to the plate while maintaining contact relation between said form and distributing rollers.

2. Inking mechanism for printing presses and the like, comprising in combination, an ink distributing roller system, a series of form rollers, adjustable eccentric means for establishing contact relation of the latter with certain ones of the distributing rollers, additional adjustable eccentric means for contacting the form rollers with a printing plate, and mechanism for actuating said latter means for the purpose of tripping the latter rollers with respect to the plate while maintaining contact relation between said form rollers and said distributing rollers.

3. In a printing press, the combination of inking mechanism comprising a printing plate carrier having a gap therein, an ink distributing roller system including a plurality of distributing rollers, a series of form rollers to receive a supply of ink therefrom and apply a film of ink to the plate on said carrier, said form rollers having an operative position in contact with the plate and a tripped position spaced from said plate, supporting arms for each of said form rollers arranged to move therewith between operative and tripped positions, manually operable means including an eccentric member rotatably mounted in each of said arms for adjusting the position of the arms and thereby the contact relation of each form roller independently with respect to the printing plate while in their operative position, cam actuated mechanism having a connection with each eccentric member for automatically rocking said members whereby to raise said arms and thereby trip the form rollers sequentially in pairs off said plate as the gap in the plate carrier passes thereunder, and additional means associated with each supporting arm for maintaining the contact relation between the form rollers and their respective distributing rollers constant for both positions of said form rollers.

4. In a printing press, the combination of a printing plate carrier having a gap therein and inking mechanism comprising an ink distributing roller system including a plurality of distributing rollers having fixed axes of rotation, a series of form rollers in contact relation with the latter to receive a supply of ink therefrom and to apply

a film of ink to the printing plate, independently adjustable supporting arms for journaling each form roller, manually operable means including an eccentric member revolvably mounted in each of said arms for adjusting the position of said arms and thereby the contact relation between the respective form rollers and the printing plate, mechanism having automatic operation to rock said same eccentric members for sequentially tripping the form rollers in pairs on and off said plate while passing said gap, and additional mechanism pivotally connected to said arms for maintaining a predetermined contact relation between the form rollers and their respective distributing rollers notwithstanding the tripping 15 movement of said form rollers.

HENRI E. PEYREBRUNE.
